Attorney

UNITED STATES PATENT OFFICE.

L. LEWIS SAGENDORPH, OF CINCINNATI, OHIO, ASSIGNOR OF ONE-HALF TO
HARLAN P. LLOYD, OF SAME PLACE.

SHEET-METAL ROOFING.

SPECIFICATION forming part of Letters Patent No. 312,658, dated February 24, 1885.

Application filed May 27, 1884. (No model.)

To all whom it may concern:

Be it known that I, L. LEWIS SAGENDORPH, a citizen of the United States, residing at Cincinnati, Ohio, have invented new and useful 5 Improvements in Sheet-Metal Roofing, of which the following is a specification.

My invention relates to a new and useful improvement in holding-cleats for sections of sheet-metal roofing, its object being to secure 10 a cheap, efficient, and durable method and means of holding together the adjacent edges of sheet-metal roofing.

To this end my invention consists of a strip 15 of metal embodying one or more movable tongues detached at the sides and at one end from the surrounding metal, the other end being incorporated with and forming part 20 of the strip, the cleat being of a length sufficient to overlap the adjacent turned-up edges of roofing-sections, and to permit on one side 25 of being fastened to the sheathing by nails, screws, or otherwise, the other side being so constructed that there is no closed or V-shaped angle for the lodgment of water, and the consequent corroding and destruction of its parts, 30 as has heretofore been the case in devices of this character.

My invention is illustrated in the accompanying drawings, in which Figure 1 is a plan 35 view or horizontal projection of the strip containing a tongue; Fig. 2, a perspective view of the holding-cleat in position; Fig. 3, a sectional end elevation of a roofing-strip with the cleat applied; Fig. 4, another sectional view showing two adjacent strips placed together, one having an overlapping edge, and 40 the holding-cleat in position; and Fig. 5, a sectional elevation of two roofing-strips, with the addition of a covering-cap and the holding-cleat.

In the drawings, A designates the strip of metal constituting the holding-cleat, and a the tongue cut from the strip, leaving the base uncut, so that the tongue can be bent 45 away from the strip to allow the insertion of the overlapping edge of the adjacent roofing-sheet.

The holding-cleat is intended to be applied to roofing-sheets having upturned edges, as 50 shown at B, Figs. 2, 3, 4, and 5, the manner of its use being as follows: The strip A, being first bent at a right angle on the line x x,

Fig. 1, is applied against the outside of the upturned edge c of the roofing-sheet B and nailed to the roof-sheathing, as shown in Fig. 55 3, the tongue a being at the same time bent outward away from the vertical portion of the covering-sheet. If the adjacent covering-sheet has a turn-over edge, it is applied as shown in Fig. 4, overlapping the edge c inside of the tongue, the latter being then bent over the several parts, clamping the whole firmly together. If the adjacent covering-sheet has an upturned edge of equal height with the first, it is only necessary to cover the 60 exposed edges by a covering-cap and bend the tongue of the holding-cleat over all, as before, and as shown in Fig. 5.

The holding-cleats are used at such intervals as will securely retain the sheets against 70 the force of winds; and it will be apparent that by this mode of securing the same the ordinary expansion and contraction of the sheets is freely permitted without causing 75 leaks or impairing the strength of the joint. It is also to be observed that by the construction of the cleat and the manner of its application to the covering-sheets any moisture that 80 might find its way between the sides of the tongue and the strip from which it is cut will readily pass downward against the side of the upturned edge of the covering-sheet and escape without lodgment, and consequently 85 cause no rusting or injury to the parts. Another advantage is the economy of material 90 over previous devices, by reason of the construction and method of applying the cleat.

I claim as my invention and desire to secure by Letters Patent—

A holding-cleat consisting of a strip of 90 metal embodying one or more tongues detached at the sides and at one end from the surrounding metal, and adapted to be bent over the upturned edges of adjacent metal roof-sheets, substantially as and for the purposes set forth.

In testimony whereof I have hereunto set my hand in the presence of two subscribing witnesses.

L. LEWIS SAGENDORPH.
